BILGE PUMP OPERATING MEANS

Frederick Perkins, Jamaica, N. Y., assignor to
 Perkins Marine Lamp & Hardware Corp., New
 York, N. Y., a corporation of New York

Application February 12, 1943, Serial No. 475,621

5 Claims. (Cl. 103—205)

This invention relates to marine equipment. More particularly it pertains to manually operable reciprocating bilge pumps.

Heretofore it has been the practice to provide pumps of this type with a stirrup handle which was directly attached to the plunger rod. Such handle was adapted to be operated by direct lifting so that a person manipulating the same in an open boat, such as a life boat, had to stand over the pump, where he rocked the boat, was in danger of falling or being washed overboard, and was so cramped that he could not work very long.

Accordingly, it is the main object of the invention to provide a marine pump of the character described which can be operated easily by a person who is sitting naturally on a thwart near a gunwale.

An ancillary object of the invention is to provide a pump capable of being operated in the foregoing manner because it has an operating oscillating shaft which extends perpendicular to and transects the longitudinal axis of the pump barrel.

A further object of the invention is to provide a pump of the character described which shall comprise relatively few and simple parts, be easy to assemble and rugged in construction, and which shall operate with a high degree of efficiency.

Other objects of this invention will in part be obvious and in part hereinafter pointed out.

The invention accordingly consists in the features of construction, combinations of elements and arrangement of parts which will be exemplified in the constructions hereinafter described, and of which the scope of application will be indicated in the appended claims.

In the accompanying drawings, in which are shown various possible embodiments of this invention and wherein like numbers refer to like parts throughout,

Fig. 1 is a fragmentary transverse section through a life boat showing in side elevation a bilge pump mounted on said boat and embodying my invention;

Fig. 2 is a fragmentary longitudinal section through the boat showing the pump in front elevation;

Fig. 3 is an enlarged sectional view of the pump taken substantially along the line 3—3 of Fig. 2;

Fig. 4 is an enlarged sectional view of the pump taken substantially along the line 4—4 of Fig. 1;

Figs. 5 and 6 are sectional views taken sub-

stantially along the lines 5—5 and 6—6, respectively, of Fig. 3;

Fig. 7 is a sectional view similar to Fig. 4 of a pump embodying a modified form of my invention, and

Fig. 8 is a sectional view taken substantially along the line 8—8 of Fig. 7.

Referring now to the drawings and more particularly to Figs. 1 through 6, 10 denotes a manually operable reciprocating bilge pump embodying my invention and permanently mounted on the gunwale of a life boat 12.

The pump includes a barrel 14 upon whose lower end there is screwed a threaded intake fitting 16. This fitting is provided, as is usual in the art, with a hose coupling portion 18 and a threaded pipe coupling portion 20. In the illustrated embodiment, I have shown an intake pipe 22 connected to the fitting 16 by means of a pipe coupling 24. The pipe 22 extends through the floor grating 26 of the life boat and terminates at a strainer 28 submerged in the sump.

A discharge fitting 30 is screwed to the top end of the pump barrel 14. This fitting may comprise a tapered reducing coupling whose inner surface is of conical shape and is adapted to present a minimum friction head opposing water flow therethrough. The smaller end of the fitting 30 is tapped for connection to a suitable outlet 20 conduit which in this instance comprises a nipple 31 to which a rubber hose 32 is attached by a hose clamp C.

A plunger 34 is slidably received within the barrel 14. Said plunger is provided with a gravity check valve comprising a heavy disc 36 of slightly less diameter than the internal diameter of the barrel 14. The disc is grooved around its rim to form a slot 38 in which there is fitted packing 40 forming a water-tight sliding joint 40 with the inner surface of the barrel. A plurality of circularly arranged apertures 42 communicate between the top and bottom surfaces of the disc 36. The center of the disc is tapped to securely engage the lower threaded extension 44 of a center post 46 by means of which the plunger 34 is reciprocated.

A valve plate 48, faced on its under surface with a yielding, resilient material such as leather 50, is centrally and slidably mounted on the post 46, being of such dimensions that when allowed to descend it will close off the top ends of the apertures 42, as shown in Fig. 4. The valve plate 48, however, is light enough, as is well known in the art, to be easily lifted on the down stroke of the plunger 34 by water rushing through said

apertures. Upward movement of the plate 48 is limited by a pin 52 which extends through the post 46. The plate 48 reciprocates in a cage formed by a plurality of tubular sleeves 54 erected around the circumference of the disc 35 and there held by long-shanked screws 56. The upper ends of the sleeves 54 are tied together by a ring 58 secured to the sleeves by said screws. In addition to affording protection to the plate 48, the cage, and particularly the ring 58, aid in preventing tilting of the plunger 34.

Another check valve is provided at the intake end of the barrel 14 which cooperates with the check valve in the plunger 34 to permit the pump to function as a lift pump. This second check valve is also of the gravity type and includes a sheet 60 having a frusto-conical downwardly extending and centrally disposed annular boss 62. Said boss acts as a valve seat and is supported by the conical walls of a central recess 64 in the intake fitting 16. A hollow ball 66, having a diameter slightly less than the upper diameter of the boss, rests on the valve seat. The weight of the ball is such that the ball will be readily raised off the valve seat by water which flows into the barrel 14 when the plunger 34 is lifted. The ball is covered by a second disc 68 overlying the disc 60 and provided with a central raised and perforated retainer 68 which freely accommodates said ball. The periphery of at least the upper of the two discs 66, 68 is caught between the bottom of the barrel 14 and the intake fitting 16 whereby both said discs are firmly held in position.

It will be appreciated that when the plunger 34 is reciprocated in the pump barrel 14, the plunger check valve and ball check valve will cause water to be drawn through the strainer 28 and discharged from the spout 32 according to the well known principle of operation of a lift pump. If desired check valves of other types, for example, clapper valves or spring loaded valves, may be employed in the plunger and intake.

In accordance with my invention, I have provided for reciprocating the plunger 34 a means which is of novel construction and arrangement and which is adapted to permit easy operation of the pump when it is mounted in positions in which it heretofore has been considered difficult and awkward to operate. An example of such mounting is on the gunwale of a boat where the pump is to be operated by a person sitting on a boat thwart. In general said novel means is so constructed that the pump operating handle can be substantially horizontally oscillated in a plane parallel to and spaced from the axis along which the plunger reciprocates and spaced from the surface on which the pump is mounted. This is preferably accomplished by disposing the oscillating drive shaft perpendicular to and transecting the longitudinal axis of the pump barrel 14. To this end, said means may comprise an oscillatable operating shaft 70 which is rotatably journaled in a stuffing box 72 connected by integral casting, bolting, brazing or welding to the outside of the barrel 14 near the outlet end. The stuffing box may include a stuffing box cylinder 76 whose flange base 74 is arcuately fashioned to conform negatively to the external contour of the pump barrel, the connection to the barrel being made, if the cylinder is not cast integral with the barrel, around the flange. A gland 78 threadedly engages the stuffing box cylinder and urges a bush 80 against packing 82 surrounding the shaft 70.

One end 84 of the operating shaft extends into the pump barrel through an aperture in a wall thereof. This end is reduced in diameter to provide a shoulder 86 which rests on the outer surface of the pump barrel and prevents the shaft, when positioned properly, from axially shifting further into said barrel. A crank plate 88 is disposed on the inner shaft end 84, being held in this position by a set screw 89 which is threadedly received in a hub 90 on the crank plate and frictionally engages the operating shaft. A spacing collar 91, interposed between the hub 90 and wall of the pump barrel, prevents the operating shaft 70 from shifting axially outwardly. The crank plate 88 is connected to the center post 46 by a pitman 92 whose lower end is pivotally received on a pin 94 extending between the spaced arms 96 of a yoke integrally formed on the top of the center post 46. The upper end of the pitman is rotatably connected to the crank plate by a nut and bolt 98 which serves as a crank pin.

The protruding end 100 of the operating shaft 70, which extends exteriorly of the stuffing box 72, is squared for slidably but non-rotatable reception in the square aperture 102 of an operating lever handle 104. A set screw 106 is employed to lock the handle to the shaft. If desired, a hardwood grip 108 may be wedged to the shank 110 of the handle and maintained in this position by a ferrule 112. Preferably the handle is arranged to be vertically disposed when the plunger is in its lowermost position (Figs. 1 and 3), this being accomplished by loosening the set screw 89 and relatively rotating the shaft 70 and crank plate 88.

The pump 10 is mounted on the gunwale by a pair of brackets 114, 116, each of which includes a ring 118 snugly but slidably encircling the pump barrel. One ring is adapted to be abutted against the bottom of the outlet fitting 30 and the other against the top of the intake fitting 16. The rings each carry an integrally connected plate 120 which is screwed to stay strips 122 running around the gunwales.

In Fig. 8 I have shown a bilge pump 210 embodying a modified form of my invention. The cylinder 214, plunger 234, intake fitting 216 and lower check valve (not shown) are all similar to the barrel, plunger, intake fitting and lower check valve described with reference to Figs. 1 through 6. The novel means for reciprocating the plunger, however, is so arranged that no radial pressure is placed upon the packing 240 in the plunger disc 236. Said plunger 236 has screwed in its central tapped aperture a plunger rod 324 which is force-fitted into a downwardly extending socket 326 on a Scotch yoke 328. A guide rod 330 is force-fitted into an upwardly extending socket 332 on said yoke. Said guide rod is slidably received in the bore of a hub 334 centrally held above the pump barrel 214 by spider arms 336 extending radially inward from the outlet fitting 230. The yoke 328 is actuated by a nut and bolt 298 slidably received in the yoke crossway 338 and attached to the crank plate 288. Said crank plate is supported and operated in the same manner as the crank plate 88 shown in the first described form of my invention.

It will thus be seen that I have provided a reciprocating manually operatable marine bilge pump which achieves the several objects of the invention and which is well adapted to meet the conditions of practical use.

As various embodiments might be made of

the above invention and as various changes might be made in the embodiments above set forth, it is understood that all matter herein set forth or shown in the accompanying drawings is to be interpreted as illustrative and not in a limiting sense.

Having thus described my invention, I claim as new and desire to secure by Letters Patent:

1. For use in a manually operatable reciprocating marine bilge pump comprising an elongated barrel of uniform diameter and a plunger reciprocatable within said barrel: a bilge pump operating means for reciprocating said plunger, said means comprising a stuffing box mounted directly on a barrel wall and disposed wholly externally thereof, an oscillatable operating shaft rotatably supported in said stuffing box with its axis extending perpendicular to and transecting the longitudinal axis of said barrel, one end of said shaft extending exteriorly of said stuffing box, an operating lever handle secured to said shaft end, the other end of said shaft extending freely interiorly of said barrel, and means secured to said other end and connecting the latter and said plunger to transform rotary oscillatory movement to linear reciprocating movement, said motion transforming means including a crank pin and a Scotch yoke.

2. For use in a manually operatable reciprocating marine bilge pump comprising an elongated barrel of uniform diameter and a plunger reciprocatable within said barrel: a bilge pump operating means for reciprocating said plunger, said means comprising a stuffing box mounted directly on a barrel wall and disposed wholly externally thereof, an oscillatable operating shaft rotatably supported in said stuffing box with its axis extending perpendicular to and transecting the longitudinal axis of said barrel, one end of said shaft extending exteriorly of said stuffing box, an operating lever handle secured to said shaft end, the other end of said shaft extending freely interiorly of said barrel, a Scotch yoke connected to said plunger and mounted for linear reciprocation parallel to the longitudinal axis of said barrel, and a member oscillated by movement of said handle and slideable in the slot of said yoke to linearly reciprocate the same, as said handle is oscillated.

3. For use in a manually operatable reciprocating marine bilge pump comprising an elongated barrel of uniform diameter and a plunger reciprocatable within said barrel: a bilge pump operating means for reciprocating said plunger, said means comprising a stuffing box mounted directly on a barrel wall and disposed wholly externally thereof, an oscillatable operating shaft rotatably supported in said stuffing box with its axis extending perpendicular to and transecting the longitudinal axis of said barrel, one end of

- said shaft extending exteriorly of said stuffing box, an operating lever handle secured to said shaft end, the other end of said shaft extending freely interiorly of said barrel, the end of said shaft inside the barrel being of a lesser diameter than the diameter of the shaft outside the barrel, and the aperture in the barrel wall through which said shaft end passes being of lesser diameter than the diameter of the shaft outside the barrel wall, and means secured to said other end and connecting the latter and said plunger to transform rotary oscillatory movement to linear reciprocating movement.
4. For use in a manually operatable reciprocating marine bilge pump comprising an elongated barrel of uniform diameter and a plunger reciprocatable within said barrel: a bilge pump operating means for reciprocating said plunger, said means comprising a stuffing box mounted directly on a barrel wall and disposed wholly externally thereof, an oscillatable operating shaft rotatably supported in said stuffing box with its axis extending perpendicular to and transecting the longitudinal axis of said barrel, one end of said shaft extending exteriorly of said stuffing box, an operating lever handle secured to said shaft end, the other end of said shaft extending freely interiorly of said barrel, the end of said shaft inside the barrel being of a lesser diameter than the diameter of the shaft outside the barrel, and the aperture in the barrel wall through which said shaft end passes being of lesser diameter than the diameter of the shaft outside the barrel wall, a member mounted on said shaft and abutting the inside of the barrel adjacent said shaft, and means secured to said other end and connecting the latter and said plunger to transform rotary oscillatory movement to linear reciprocating movement.
5. For use in a manually operatable reciprocating marine bilge pump comprising an elongated barrel of uniform diameter and a plunger reciprocatable within said barrel: a bilge pump operating means for reciprocating said plunger, said means comprising a stuffing box mounted directly on a barrel wall and disposed wholly externally thereof, an oscillatable operating shaft rotatably supported in said stuffing box with its axis extending perpendicular to and transecting the longitudinal axis of said barrel, one end of said shaft extending exteriorly of said stuffing box, an operating lever handle secured to said shaft end, the other end of said shaft extending freely interiorly of said barrel, means to prevent axial shifting of said shaft, and means secured to said other end and connecting the latter and said plunger to transform rotary oscillatory movement to linear reciprocating movement.

FREDERICK PERKINS.
